Edward Wright.

ATTORNEY

UNITED STATES PATENT OFFICE.

FREDERICK M. WHYTE, OF TARRYTOWN, NEW YORK.

METAL ROOF FOR CARS.

1,836,993.

Specification of Letters Patent. Patented Apr. 13, 1920.

Application filed August 15, 1919. Serial No. 317,679.

To all whom it may concern:

Be it known that I, FREDERICK M. WHYTE, a citizen of the United States, residing at Tarrytown, in the county of Westchester 5 and State of New York, have invented a certain new and useful Improvement in Metal Roofs for Cars, of which improvement the following is a specification.

This invention relates to car roofs, and 10 more particularly to metal roofs as applied to freight cars or box cars, the object being to provide an improved roof of the type having metal roofing sheets extending between the carlines, and in which each roofing sheet is rigidly secured along one of its 15 side edges while the opposite side edge at the adjacent carline is free to slide to compensate for the twisting and weaving motion of the car without subjecting the 20 roofing sheets to corresponding buckling stresses.

Another object is to provide improved means for covering and weather-proofing the space between the side edges of the 25 adjoining roofing sheets at each carline.

Another object is to provide an improved construction whereby any one of the metal roofing sheets may be detached and removed for repairs or renewal without disturbing 30 the adjoining roofing sheets.

Another object is to provide an improved end sheet construction whereby the two opposite end sheets of the car roof are made alike and interchangeable.

35 With these and other objects in view, my invention comprises certain improved features of construction which will now be more fully described and claimed.

In the accompanying drawings: Figure 1 40 is a transverse section taken on the line 1—1 of Fig. 2, extending slightly more than half the width of the car, and showing a metal roof embodying my improvement; Fig. 2, a side elevation of the same with 45 portions broken away; Fig. 3, a longitudinal section of the same, taken substantially on line 3—3 of Fig. 1, and showing the carlines at the opposite ends of the car and one of the intermediate carlines; Fig. 4, a 50 transverse section of one of the carlines upon a larger scale, and showing the covering strip and the adjoining edges of the roofing sheets; and Fig. 5, a similar sec-

tional view, but showing a modification in which the binding strip is eliminated, and 55 the roofing sheets are supported directly upon the purlins.

According to the construction shown, the carlines, 4, are supported at their ends on the side plates, 1, of the car body, in any 60 suitable manner, as, for instance, by means of brackets, 3. While the side plates are indicated as being formed of metal, it will be understood that they may be of wood or other material; also that the carlines may 65 be either of wood or metal, and of any desired shape, although I prefer to form the same of a Z bar metal section, as shown. The purlins, 5, which are preferably formed of wooden beams, may be bolted to the under side of the carlines, and extend longitudinally of the car in the usual manner. The sheathing boards, 8, when used, are supported upon the purlins in the ordinary 70 way. The metal roofing sheets, 9, in the 75 type of roof known as an outside metal roof, are laid upon the sheathing boards between the carlines and preferably extend the full width of the car from eaves to eaves.

According to my improvement, each of 80 the intermediate roofing sheets, 9, is rigidly fastened along one of its side edges to one of the carlines, while the opposite side edge is left free to slide relative to the car frame in the plane of the roof, and thereby relieve the same from any buckling stresses 85 due to the weaving and swaying motions of the car while running. As shown, the roofing sheet is provided with an upstanding rebent flange 18 secured to the carline by 90 bolts, 13, and for the purpose of distributing the clamping effect over a greater length 95 of the roofing sheets, the binding strips, 11, of wood or metal, may be mounted on the bolts, 13, for clamping the roofing sheet against the carline. The binding strips are particularly desirable where thin gage metal 100 roofing sheets are employed, as in an outside metal roof. The opposite side edge of the metal roofing sheet is preferably formed with an upstanding rebent flange 19 with a free space between the vertical portions thereof, for the purpose of preventing the entrance of water or moisture. This edge 105 of the roofing sheet is, however, left free to slide upon the sheathing boards. In or-

der to hold this edge of the roofing sheet down flat upon the roof, I preferably provide a bearing strip, 12, of wood or other suitable material, the same being supported 5 lengthwise of the carline by bolts, 14, and brackets, 15, mounted on the bolts, 13.

For covering the carlines and weather-proofing the joint between adjacent roofing sheets, I provide the covering strips or carline caps, 10, having bent down side portions inclosing the strips, 11 and 12, passing beneath the same in contact with the roofing sheets, and having upstanding flanges at the side edges. One of these 10 flanges 20 is clamped to the carline with the flange 18 of the roofing sheet, 9, by means of the strip, 11, and bolts, 13, while the vertical flange 21 at the opposite side of the carline cap interlocks with the turned 15 over side edge of the adjoining roofing sheet, thus forming a weather-proof joint. The carline caps may extend the full width of the car, but are preferably formed in sections extending a little more than one-half 20 the width of the car and overlapping each other at the ridge. The carline cap is placed in position by engaging the upper end thereof with the lower ends of the flanges 18 and 19 of the roofing sheets at the eaves, 25 and sliding the same upward along the carline. The eaves molding, 17, and flashing, 16, are secured on the side plate, 1, in the usual way, and the lower edges of the roofing sheets are bent down over the molding. 30 The lower ends of the carline caps are also bent down over the molding and fastened to the side plates.

The end roofing sheet at the right end of the car has an upstanding flange 18 at its 40 left hand side which is rigidly clamped to the carline by bolts, 13, while the right hand edge 22 is turned down over the end plate, 6, of the car, and loosely fastened thereto by nails. The end roofing sheet at the left end 45 of the car is also provided with a flange 18 along its right hand side which is rigidly clamped to the carline by means of strip, 12, and bolts, 14, while its other side edge 22 is bent down over the end plate, 6, of the 50 car, and nailed thereto. The bearing strip, 12, at this left hand carline may be formed slightly different from the other strips for clamping this roofing sheet. The two end roofing sheets are, therefore, made alike, and 55 are interchangeable.

The running board, 2, may be supported on suitable brackets, 7, fastened to the carlines and carline caps.

When my improvement is employed in 60 connection with an all metal roof in which heavy gage sheet metal is used for the roofing sheets, these may then be placed directly upon the purlins, 5, as shown in Fig. 5, and the sheathing boards, 8, need not be used. 65 In this case also the binding strip, 11, may

be eliminated, and the flanges of the roofing sheet and the carline cap may be fastened directly to the carline by the bolts, 13.

In assembling the parts of the metal roof in position, the roofing sheets are first placed 70 between the carlines, then the bolts, 13, are inserted through binding strips, 11, carline, 4, and bracket, 15, and the nuts applied loosely to said bolts; bearing strip, 12, is then fastened to the brackets, 15, by bolts, 75 14, and the covering strip, 10, is then slid into position, as before described. The nuts on bolts, 13, which are accessible from beneath the carline caps, are then tightened 80 and the roof is then complete. The running board bracket, 7, may thus be bolted or riveted to the carlines.

If it be desired to remove any one of the roofing sheets without disturbing the others, the running board brackets or saddles, 7, 85 are first removed from the adjoining carlines, the nuts of bolts, 13, are then loosened from the under side of the roof, whereupon the two carline caps may be removed; the binding strips may then be detached, and 90 the roofing sheet lifted from its position. It may then be replaced by a reversed order of operation, without disturbing the adjoining roofing sheets.

Having now described my invention, what 95 I claim as new and desire to secure by Letters Patent is:

1. In a car roof, the combination of the carlines, metal roofing sheets located between said carlines and each having one of 100 its side edges rigidly fastened to a carline and the other side edge free to slide, and carline caps covering the side edges of adjoining roofing sheets.

2. In a car roof, the combination of the 105 carlines, metal roofing sheets located between said carlines, said sheets being each provided with an upstanding flange at one side rigidly fastened to a carline and having the other side free to slide, and carline caps 110 having downturned side portions covering the side edges of adjoining roofing sheets.

3. In a car roof, the combination of the carlines, metal roofing sheets located between said carlines, said sheets being each 115 provided with an upstanding flange at one side rigidly fastened to a carline and having the other side free to slide, and a carline cap having downturned side portions, one of said sides being rigidly fastened to the carline 120 and the upstanding side flange of one of the roofing sheets.

4. In a car roof, the combination of the carlines, metal roofing sheets located between said carlines, said sheets being each 125 provided with an upstanding flange at one side rigidly fastened to a carline and having the other side free to slide, and a carline cap having a downturned side portion with a rebent upstanding flange, said flange being 130

clamped to the flange of the roofing sheet and to the carline.

5. In a car roof, the combination of the carlines, metal roofing sheets located between said carlines, said sheets being each provided with an upstanding flange at one side rigidly fastened to a carline and having the other side free to slide, and a carline cap having a downturned side portion with a 10 rebent upstanding flange, and a binding strip, for clamping the roofing sheet flange and the flange of the carline cap to the carline.

6. In a car roof, the combination of the carlines, metal roofing sheets located between said carlines, said sheets being each provided with an upstanding flange at one side rigidly fastened to a carline and having the other side free to slide, and a carline cap 20 having a downturned side portion with a rebent upstanding flange, and detachable clamping means accessible from beneath said carline cap for fastening the edge of the roofing sheet to the carline.

25 7. In a car roof, the combination of the carlines, metal roofing sheets located between said carlines, said sheets being each provided with an upstanding flange at one side rigidly fastened to a carline and having 30 the other side free to slide, and a carline cap having a downturned side portion with a rebent upstanding flange, a binding strip and bolts for clamping the flange of the roofing sheet and the carline cap to the carline, the carline cap covering the binding strip, and said bolts being accessible from beneath the carline caps.

8. In a car roof, the combination of the carlines, metal roofing sheets located between said carlines and each having one of the side edges rigidly fastened and the other side edge free to slide, and bearing means supported by the carline for holding down the free edge of the roofing sheet.

45 9. In a car roof, the combination of the carlines, metal roofing sheets located between the carlines and having one of the side edges rigidly fastened to a carline and the other side edge free to slide, a bearing 50 strip for holding down the free edge of the

roofing sheet, and brackets secured to the carline for supporting said bearing strip.

10. In a car roof, the combination of the carlines, metal roofing sheets located between the carlines and having one of the 55 side edges rigidly fastened to a carline and the other side edge free to slide, a bearing strip for holding down the free edge of the roofing sheet, and a carline cap covering said bearing strip and the sides of the adjoining 60 roofing sheets.

11. In a car roof, the combination of the carlines, metal roofing sheets located between said carlines, said sheets being provided with an upstanding flange at one side, 65 rigidly fastened to a carline, and having the other side free to slide, and a metal roofing sheet located between the end carline and the end of the car, said sheet having a side flange turned down over the end plate of the 70 car and an upstanding flange at its opposite side, rigidly fastened to the end carline.

12. In a car roof, the combination of the carlines, intermediate metal roofing sheets located between the carlines, and end roofing 75 sheets located between the end carlines and the ends of the car, the intermediate roofing sheets each having an upstanding flange at one of their side edges rigidly secured to one carline and the opposite side edge free 80 to slide, the end sheets having a downturned flange at their outer sides secured to the end plate of the car, and an upstanding flange at their inner sides rigidly clamped to the end carline, and carline caps for covering the 85 adjacent side edges of the roofing sheets.

13. In a car roof, the combination of the carlines, metal roofing sheets located between said carlines, and each having one of its side edges fastened to a carline, and the 90 other side edge free to slide, carline caps covering the side edges of adjoining roofing sheets and the carline, and running board saddles rigidly secured to the carlines and carline caps independently of the free edges 95 of the roofing sheets.

In testimony whereof I have hereunto set my hand.

FREDERICK M. WHYTE.
